UNITED STATES PATENT OFFICE.

SAMUEL A. SMITH, OF EVERTON, ARKANSAS.

MECHANICAL MOVEMENT.

1,253,437.

Specification of Letters Patent. Patented Jan. 15, 1918.

Application filed June 9, 1917. Serial No. 173,782.

To all whom it may concern:

Be it known that I, SAMUEL A. SMITH, a citizen of the United States, residing at Everton, in the county of Boone and State of Arkansas, have invented certain new and useful Improvements in Mechanical Movements, of which the following is a specification, reference being had to the accompanying drawings.

10 This invention relates to certain improvements in mechanical movements, and it is an object of the invention to provide a mechanism of this general character having novel and improved means for converting reciprocal movement into rotary movement.

It is also an object of the invention to provide a device of this general character having novel and improved means whereby 20 the possibility of a dead center is eliminated.

The invention also has for an object to provide a mechanism of this general character including a reciprocating member provided with opposed racks mounted for swinging movement and which are adapted to coact with a rotatable member, together with means for automatically rendering one of the racks inoperative when the second 30 rack is functioning.

My invention consists in the details of construction and in the combination and arrangement of the several parts of my improved mechanical movement whereby certain important advantages are attained and the device is rendered simpler, less expensive and otherwise more convenient and advantageous for use, all as will be herein-after more fully set forth.

40 The novel features of the invention will hereinafter be definitely claimed.

In order that my invention may be the better understood, I will now proceed to describe the same with reference to the accompanying drawings, wherein—

Figure 1 is a view in elevation illustrating a mechanical movement constructed in accordance with an embodiment of my invention;

50 Fig. 2 is a view in top plan of my improved construction as embodied in Fig. 1;

Fig. 3 is an enlarged sectional view taken

substantially on the line 3—3 of Fig. 2, looking in the direction of the arrow;

Fig. 4 is an enlarged sectional view taken 55 substantially on the same line as Fig. 3, but looking in the opposite direction;

Fig. 5 is an enlarged sectional view taken substantially on the line 5—5 of Fig. 2, looking in the direction of the arrow; 60

Fig. 6 is a fragmentary sectional view taken substantially on the line 6—6 of Fig. 5;

Fig. 7 is a sectional view taken substantially on the line 7—7 of Fig. 3; and 65

Fig. 8 is a view in perspective of one of the rack-operating members as herein embodied.

As disclosed in the accompanying drawings; B denotes a suitable base or foundation provided with an upstanding frame F, preferably rectangular in form and which is provided adjacent its top and bottom with longitudinally disposed guide rods 1, herein disclosed as in predetermined spaced relation 70 with respect to the inner face of the frame F. H denotes a substantially rectangular head having its central portion cut out and which is provided at its corners with laterally directed lugs 2, through which the rods 1 are freely directed so that the head H is supported for reciprocatory movement. The head H is adapted to be reciprocated in any desired manner, but preferably through the medium of a rectilinear piston rod P 80 coacting with a cylinder C in a conventional manner.

Arranged at right angles to the frame F, and positioned to one side thereof and substantially in alignment with the center of 90 the open portion of the frame F, is a shaft S; and fixed to the end portion of the shaft S adjacent the frame F is a disk D. Extending from the disk D adjacent the periphery thereof and toward the frame F 95 is a plurality of lugs or pins 3, herein disclosed as four in number and equidistantly spaced circumferentially of the disk D and extending substantially three-eighths of the distance therearound. The lugs or pins 3 100 are adapted to mesh with the racks R and R', in a manner and for a purpose to be hereinafter described.

The racks R and R' overlie corresponding

side faces of the upper and lower longitudinal portions of the head H, respectively, and have their teeth 4 inwardly directed. The racks R and R' are each pivotally engaged 5 adjacent one end portion to the head, as indicated at 5, but in reverse arrangement. As herein embodied the upper rack R has its end portion adjacent the rod P pivotally mounted, while the lower rack R' has its 10 end portion remote from the rod P pivotally mounted. The free end portion of each of the racks R and R' has bearing thereagainst a flat spring 6, for constantly urging the rack toward the limit of its inward movement, and which limit of inward movement is controlled by a laterally directed finger 7, carried by the free end portion of the rack and overlying the adjacent edge of the head H, as particularly illustrated in Fig. 6. Each of the springs 6 is anchored to the head H adjacent the pivoted end portion of the rack with which said spring coacts, as is believed to be clearly disclosed in Figs. 4 and 5.

25 In the operation of my improved mechanism the lugs or pins 3 are adapted to engage one rack during one movement of the head, and the second rack upon the reverse movement of the head. This is accomplished 30 by imparting the requisite timed swinging movement to the racks R and R'. Pivotally engaged with the frame F adjacent the opposite ends thereof are the rack operating members or cams M. The members M are 35 positioned adjacent opposite ends of the frame F and have their free end portions outwardly directed. The free end portion of each of the members M is provided with a cam face 8, which is adapted to engage 40 beneath the adjacent finger 7, to impart swinging movement to the rack R or R' for disengaging such rack from the lugs or pins 3. As is particularly illustrated in Fig. 6, the finger 7 is of such length as to extend beyond the face of the head H, remote 45 from the rack.

The members M are so positioned upon the frame F as to assure one of the racks R and R' to be engaged with the lugs or pins 50 3 at substantially the same moment the second rack is disengaged therefrom. With the head H moving in the direction as indicated by the arrow in Fig. 1, the finger 7 of the rack R will travel inwardly of and in contact with the member M, while the finger 7 of the lower rack R' will be riding over the outer or cam face of the adjacent member M. In this arrangement the rack R is 55 operatively engaged with the lugs or pins 3, while the rack R' has been swung out of contact therewith. After the head H has traveled a distance sufficient to cause the finger 7 of the rack R to pass beyond the free end of the upper member M, said member M will drop by gravity upon the stop 60 9

carried by the frame F, while the finger 7 of the lower rack will be free of its coacting member M and be forced upwardly into contact with the lugs or pins 3 by its spring 6. It will therefore be seen that upon the 70 opposite movement of the head H, the finger 7 of the upper rack R will pass over the cam face 8 of the adjacent member M and be swung into an inoperative position, while the finger 7 of the rack R' will travel over the upper or straight edge of its adjacent member M, in order to impart the desired rotation to the disk D. The upper member M normally engages its stop 9 by gravity, while the lower member M is maintained in 80 contact with its stop 9 through the medium of a flat spring 10, secured at one end to the frame F and having its free end portion contacting with the under surface of the laterally and inwardly directed lug 11 85 carried by the free end portion of the member M to one side of the cam face 8 thereof. Each of the members M is seated within a cut out portion produced in a longitudinally disposed flange 12, carried by the frame F, 90 and said flange 12 is provided with a supplemental cut out portion 14, to receive the lug 11, and the inner end of said lug 11 and the adjacent lug of the supplemental cut out portion 14 are correspondingly beveled, as indicated at 15, whereby the movement of the member M in a direction away from its stop 9 is maintained. It is also understood that the rack R or R' is not forced into operative engagement with the 100 lugs or pins 3 until after the finger 7 thereof has passed beyond the inner end portion of the flange 12.

From the foregoing description it is thought to be obvious that a mechanical 105 movement constructed in accordance with my invention is of an extremely simple and comparatively inexpensive nature and is particularly well adapted for use by reason of the convenience and facility with which it 110 may be assembled, and it will also be obvious that my invention is susceptible of some change and modification without material departure from the principles and spirit thereof and for this reason I do not wish to 115 be understood as limiting myself to the precise arrangement and formation of the several parts herein shown in carrying my invention into practice, except as herein-after claimed.

In practice the rod P is capable of traveling a distance in excess of the diameter of the disk D or the concentric line occupied by the lugs or pins 3 and in order to avoid the possibility of the piston (not shown) 125 from knocking out the heads of the cylinder (not shown) I have operatively engaged with the inner portion of the head H the swinging member 16 with which is pivotally engaged a pitman 17 which is also pivotally 130

engaged with one of the lugs or teeth 3. The distance between the centers of the pivotal connection of the pitman 17 is equal to the diameter of the concentric line in which the pins or lugs 3 are arranged and the swinging member 16 and the pitman 17 serve to limit the stroke of the piston rod P.

I claim:—

1. In combination with a member mounted for reciprocatory movement and a member mounted for rotary movement, opposed racks pivotally engaged with the reciprocatory member, pins extending from a face of the rotary member and with which the racks are adapted to engage, automatic means for forcing said racks into engagement with the pins, and automatic means coacting with the racks and alternately operating to maintain the racks out of engagement with the pins during reverse movement of the reciprocatory member.

2. In a device of the character described, a member mounted for reciprocatory movement, a second member mounted for rotary movement and provided with a series of outstanding pins, opposed racks carried by the reciprocatory member and mounted for swinging movement, automatic means coacting with each of the racks whereby one of said racks is operatively engaged with the pins of the rotating member during movement of the reciprocatory member in one direction and the second rack is in engagement with the pins upon movement of the reciprocatory member in an opposite direction.

3. In a device of the character described, a member mounted for reciprocatory movement, a member mounted for rotary movement, opposed racks carried by the reciprocatory member for engagement with the rotary member, each of said racks being mounted at one end portion for rocking movement, the mounting of one rack being opposite to the mounting of the second rack, automatic means coacting with the racks for swinging one of the racks out of engagement with the rotary member upon movement of the reciprocatory member in one direction and for swinging the second rack out of engagement with the rotary member upon movement of the reciprocatory member in the opposite direction, and means coacting with the racks for constantly urging the same into operative engagement with the rotary member.

4. In a device of the character described, a member mounted for reciprocatory movement, a member mounted for rotary movement, opposed racks carried by the reciprocatory member for engagement with the rotary member, each of said racks being mounted at one end portion for rocking movement, the mounting of one rack being opposite to the mounting of the second rack,

the free end portions of the racks being provided with laterally directed fingers, means coacting with the fingers for swinging the racks out of engagement with the rotary member, said means rendering one of the racks inoperative upon movement of the reciprocatory member in one direction and the second member inoperative upon movement of the reciprocatory member in the opposite direction, and means for engaging the racks with the rotary member when free of the last named means.

5. In a device of the character described, a member mounted for reciprocatory movement, a member mounted for rotary movement, opposed racks carried by the reciprocatory member for engagement with the rotary member, each of said racks being mounted at one end portion for rocking movement, the mounting of one rack being opposite to the mounting of the second rack, the free end portions of the racks having laterally directed fingers, a swinging member coacting with a finger of each of the racks and mounted for limited swinging movement, said finger passing under said swinging member upon movement of the reciprocatory member in one direction, and over the swinging member upon movement of the reciprocatory member in the opposite direction to disengage the rack from the rotary member, and means for constantly urging the racks toward the rotary member.

6. In a device of the character described, a member mounted for reciprocatory movement, a member mounted for rotary movement, opposed racks carried by the reciprocatory member for engagement with the rotary member, each of said racks being mounted at one end portion for rocking movement, the mounting of one rack being opposite to the mounting of the second rack, the free end portions of the racks having laterally directed fingers, a swinging member coacting with a finger of each of the racks and mounted for limited swinging movement, said finger passing under said swinging member upon movement of the reciprocatory member in one direction, and over the swinging member upon movement of the reciprocatory member in the opposite direction to disengage the rack from the rotary member, means for constantly urging the racks toward the rotary member, and automatic means coacting with one of the swinging members for constantly urging the same toward the limit of its movement in one direction.

7. In combination with a member mounted for reciprocatory movement and a member mounted for rotary movement, co-acting means carried by the members for rotating the rotatable member upon reciprocation of the reciprocating member, and co-acting means carried by said members and operat-

ing independently of the first named means for limiting the strokes of the reciprocating member.

8. In combination with a member mounted for reciprocatory movement and a member mounted for rotary movement, co-acting means carried by the members for rotating the rotatable member upon reciprocation of the reciprocating member, a swinging member engaged with the reciprocating member,

Copies of this patent may be obtained for five cents each, by addressing the "Commissioner of Patents, Washington, D. C."

and a pitman pivotally engaged with the rotating member and with the swinging member.

In testimony whereof I hereunto affix my signature in the presence of two witnesses. 15

SAMUEL A. SMITH.
